J. EPSTEIN,
METALLIC SPRING MATTRESS,
APPLICATION FILED MAR. 18, 1918.

1,307,543.

Patented June 24, 1919.

UNITED STATES PATENT OFFICE.

JOSEPH EPSTEIN, OF BROOKLYN, NEW YORK.

METALLIC SPRING-MATTRESS.

1,307,543.

Specification of Letters Patent. Patented June 24, 1919.

Application filed March 18, 1918. Serial No. 223,109.

To all whom it may concern:

Be it known that I, JOSEPH EPSTEIN, a citizen of the United States, and a resident of Brooklyn, in the county of Kings and

5 State of New York, have invented certain new and useful Improvements in Metallic Spring-Mattresses, of which the following is a specification.

The invention pertains to metallic spring 10 fabrics for use on beds, and it consists in the novel features and structure hereinafter described, and particularly pointed out in the claims. The spring of my invention comprises a main carrying frame and a fabric 15 composed of interengaged links of special outline connected by coiled springs with the end bars of said frame and at their side edges with flat bars which extend above the side bars of the aforesaid frame and are connected at their ends by coiled springs with the aforesaid end bars, the structure as a whole being complete in itself and adapted to be handled as a unit and applied to or removed from the customary bedstead. One of 20 the essential objects of my invention is to provide a fabric whose links may be readily assembled and which will have a special yielding action due to their particular shape. Each link has parallel sides for a definite 25 length and thence converging sides terminating at their point of approximate juncture with an eye into which an adjacent link may be hooked. At the ends of the parallel sides of the links are formed hooks to engage the eyes of adjacent links in series. 30

The invention will be fully understood from the detailed description hereinafter presented, reference being had to the accompanying drawings, in which:

40 Figure 1 is a top view, partly broken away, of a spring constructed in accordance with and embodying the invention;

Fig. 2 is a top view on a larger scale of one corner portion of the same;

45 Fig. 3 is a horizontal section through a portion of the same, taken about on the dotted line 3—3 of Fig. 2;

Fig. 4 is a detached perspective view of one of the links employed generally throughout the spring, and

50 Fig. 5 is a perspective view of a special shape of link which I employ at opposite side edges of the spring for connecting the fabric with the side or edge bars therefor.

55 In the drawings, the main rigid frame for supporting the spring fabric is numbered 10

and comprises side bars 11 and angle end bars 12, which bars 12 have upturned members 13 to which the spring fabric is, by means of coiled springs 14, tautly connected. 60

The fabric is composed of the main individual links 15 (Fig. 4) and edge links 16 of modified construction and one of which is shown in Fig. 5. The links 15 correspond in construction with one another and one of 65 said links is shown in Fig. 4, and each of the links 15 has parallel side members 17 and converging side members 18, and at the point of juncture between the members 17, 18 the link is bent at an angle, as shown at 70 19. The converging side members 18 terminate in an eye 20 which is on the longitudinal center line of the link and constitutes one end thereof. The side members 17 are formed with hooks 21, 22, respectively, which 75 represent the opposite end of the link or the end opposite to the eye 20. The special construction of the sides of the links 15, these sides having the angles 19, parallel members 17 and converging members 18, constitutes 80 an important feature of my invention, said sides having been given the special construction shown and described so as to obtain a yielding action at the angles 19 when the fabric is in use. 85

The first row of links 15, starting from the head end of the main frame, are connected with the adjacent springs 14 by means of small plates 23 which have end eyes 24 to receive hooked ends of the said springs 14 90 and eyes 25 into which adjacent hooks 21, 22 of the links 15 are caught, as shown at the upper portion of Fig. 2. The links 15 are arranged in parallel transverse rows and the members 17 of adjacent links come together 95 in the assembled fabric. The links 15 in the first or top row, looking at Fig. 2, receive in their eyes 20 the hook-ends 21, 22 of the links 15 in the next adjacent row of links, and this method of assembling is carried out 100 throughout the fabric and whereby the eyes of one row of links 15 are in line with the side members 17 of adjacent links in the next adjacent row. The row of links at the other end of the main frame 10 or at the lower end, looking at Fig. 1, have their eyes 105 20 caught upon the hooked inner ends of the adjacent springs 14, the plates 23 in this instance not being required for connecting the fabric to the said springs 14, shown at the 110 lower end of Fig. 1.

The side or edge links 16 have a side mem-

ber 26 to lie against a member 17 of the next adjacent link 15 in transverse series, an outwardly inclined side member 27 corresponding substantially with one of the side members 18 of the links 15, an eye 28 to receive the hook-end of one of the side members 17 of the adjacent link in the next transverse row of links, as shown at the left hand portion of Fig. 2, and an arm 29 having on its 10 end a hook 30 to enter a hole 31 in the longitudinal flat bar 32 which extends longitudinally of the main frame 10. Links 16 will be provided at each edge of the spring fabric, and these links will engage the bars 32, 15 which are above the sides 11 of the main frame 10 and are connected at their ends by springs 33 with the end members 12 of said main frame 10.

I employ the links 16, which represent about one longitudinal half of a link 15, so as to permit me to fill out the fabric as nearly as possible to the side bars 32 and to render it convenient to connect the side edges of the fabric with the aforesaid bars 32. The links 16 are angular, as at 34, at the juncture between their side members 26, 27, and in this regard the links 16 match the adjacent sides of the adjacent links 15. The links 16 have at the outer ends of their 30 side members 26 the hooks 35, and these hooks 35 at one end of the fabric are engaged within the eyes 25 of the plates 23, as shown in Fig. 2, and at all other portions of the fabric the hooks 35 of said links 16 35 engage eyes 20 of links 15. The side members 26, 27 of the links 16 are substantially co-equal in length, and the side members 17, 18 of the links 15 are substantially co-equal in length and also substantially co-equal in 40 length respectively with the side members 26, 27 of the links 16.

My invention as a whole has been designed with a view of producing a highly efficient, desirable, durable and easily constructed 45 spring for a bedstead, and my invention resides in the special formation of the links 15 I have designed and also in the special construction of the links 16 for coöperation with the links 15 and with the downwardly 50 yieldable flat sheet metal bars 32 to which said links 16 are connected and which links 16 serve to connect the side edges of the fabric as a whole with said bars 32. The bars 32 are flexible so as to yield downwardly, and they also may yield with the 55 fabric of the spring as a whole, since said bars are connected at their ends with the coiled springs 33.

What I claim as my invention and desire 60 to secure by Letters-Patent, is:

1. A bed-spring of the character described comprising a rigid carrying frame, coiled springs connected with the end members

thereof, yieldable side-bars above the sides of said frame and connected by the outer 65 of said coiled springs with the end members of said frame, and a fabric connected with the inner ends of the other of said coiled springs, said fabric comprising links connecting the same at its side edges with the 70 said bars and links in a series of transverse rows, the links of each row having parallel side members, converging side members extending therefrom, eyes at the juncture of the converging side members and hooks at 75 the outer ends of the parallel side members, with the hooks of adjacent matching parallel side members of adjacent links engaged with the eyes of the links in the next adjoining row of links, and the links connecting 80 the edges of said fabric with said side bars having hooked side members to engage the eyes in the adjacent side links of said rows of links, eyes to receive the hooked ends of side members of said rows of links and arms 85 having hooked ends to engage holes in said side bars.

2. A bed-spring of the character described comprising a rigid carrying frame, coiled springs connected with the end members 90 thereof, yieldable side-bars above the sides of said frame and connected by the outer of said coiled springs with the end members of said frame, and a fabric connected with the inner ends of the other of said coiled springs, 95 said fabric comprising links connecting the same at its side edges with the said bars and links in a series of transverse rows, the links of each row having parallel side members, converging side members extending 100 therefrom, eyes at the juncture of the converging side members and hooks at the outer ends of the parallel side members, with the hooks of adjacent matching parallel side members of adjacent links engaged with the 105 eyes of the links in the next adjoining row of links, and the links connecting the edges of said fabric with said side bars having straight side members which are parallel with the parallel side members of the aforesaid rows of links, inclined side members conforming to converging side members of the said rows of links, eyes at the ends of said inclined side members to receive the hooked ends of adjacent side members of 110 said rows of links, arms having hooked ends to engage holes in said side bars and hooks on said straight side members to engage said eyes in said transverse rows of links.

Signed at New York city, in the county 120 of New York, and State of New York, this 16th day of March, A. D. 1918.

JOSEPH EPSTEIN.
